DESIGN FOR A BLOUSE

Irving Geist, New York, N. Y.

Application September 20, 1935, Serial No. 58,623

Term of patent 3½ years

To all whom it may concern:

Be it known that I, Irving Geist, a citizen of the United States of America, residing in Manhattan, county of New York, and State of New York, have invented a new, original, and ornamental Design for a Blouse, of which the following is a specification, reference being had to the accompanying drawing, forming part thereof, wherein,

The dotted lines on the collar, belt, revers, and extending down the front panel portion of the blouse, represent stitchings.

I claim:

The ornamental design for a blouse, substantially as shown, and described.

IRVING GEIST.
